(57) **CLAIM**

The ornamental design for a panel insert, as shown and described.

DESCRIPTION

FIG. 1 is a perspective view of a panel insert fully assembled.

FIG. 2 is a front view of the panel insert of FIG. 1.

FIG. 3 is a back view of the panel insert of FIG. 1.

FIG. 4 is a left side view of the panel insert of FIG. 1.

FIG. 5 is a right side view of the panel insert of FIG. 1.

FIG. 6 is a top plan view of the panel insert of FIG. 1.

FIG. 7 is a bottom plan view of the panel insert of FIG. 1.

FIG. 8 is a perspective view of the panel insert of FIG. 1 shown partially disassembled.

FIG. 9 is a front view of the panel insert as shown in FIG. 8.

FIG. 10 is a back view of the panel insert as shown in FIG. 8.

FIG. 11 is a left view of the panel insert as shown in FIG. 8.

FIG. 12 is a right view of the panel insert as shown in FIG. 8.

FIG. 13 is a top plan view of the panel insert as shown in FIG. 8.

FIG. 14 is a bottom plan view of the panel insert as shown in FIG. 8; and,

FIG. 15 is a perspective view of a panel insert of FIG. 1 shown completely disassembled.
